UNITED STATES PATENT OFFICE.

HENRY M. SUTTON, WALTER L. STEELE, AND EDWIN G. STEELE, OF DALLAS, TEXAS.

ELECTROSTATIC MAGNETIC SEPARATOR.

SPECIFICATION forming part of Letters Patent No. 794,647, dated July 11, 1905.

Application filed February 3, 1902. Serial No. 92,370.

To all whom it may concern:

Be it known that we, HENRY M. SUTTON, WALTER L. STEELE, and EDWIN G. STEELE, citizens of the United States, residing at Dallas, in the county of Dallas, State of Texas, have invented certain new and useful Improvements in Electrostatic Magnetic Separators, of which the following is a specification, reference being had therein to the accompanying drawings.

This invention relates to an electrostatic magnetic separator, and more particularly to a magnetic separator in which the separation is assisted by the presence of static electricity.

The invention has for an object to produce an apparatus for accomplishing the most efficient magnetic separation in which the action of a magnetic roller is assisted and materially improved by the presence of a static current, which separation is also adapted to remove therewith very fine values of gold, which can be subsequently separated by a magnetic treatment alone.

A further object of the invention is to provide an improved form of magnetic separator and also of a cleaner-roller adapted to remove the material attracted to the magnetic roller.

Another object of the invention is to provide a statically-charging moving surface beneath the magnetic rolls, which rolls are inductionally charged from the frame of the machine with a static current in addition to the magnetic current generated therein.

Other and further objects and advantages of the invention will be hereinafter set forth and the novel features thereof defined by the appended claims.

In the drawings, Figure 1 is a side view of the apparatus. Fig. 2 is an end view of the 40 delivery end with parts broken away and in section to show the cleaner-roller and conveyor to deliver therefrom. Fig. 3 is a longitudinal section; Fig. 4, a vertical section on line 4-4 of Fig. 3. Fig. 5 is a diagrammatic 45 illustration of the magnetic separation assisted by the static in connection with a subsequent static separation for the removal of the gangue from the remaining metallic parts. Fig. 6 is a detail longitudinal section through the mag-

netic roller and the cleaner-roller; Fig. 7, an 50 enlarged sectional detail of the adjacent peripheries of these parts. Fig. 8 is a diagram illustrating the winding of the magnetic roller. Fig. 9 is a vertical section of a modified form of the magnetic roller and cleaner, and Fig. 55 10 is a detail section showing the layers of the conveying-belt and the rubber-coated roller therefor.

Like letters of reference refer to like parts in the several figures of the drawings. 60

In the form of apparatus herein shown the letter A designates a suitable construction of framework mounted upon an insulated base, as at A', and provided at its lower portion with an inclined hopper A², extending the 65 length thereof and having a central discharge-spout A³. Above this hopper a conveying-belt S is suitably mounted—for instance, upon rollers Q, which are thoroughly insulated from the shaft Y by means of a disk Q' of insulating material. The belt S is formed of rubber or other suitable insulating material 70 and is provided upon both faces with a metallic coating m, so as to form a condenser or practically an extended Leyden jar, as 75 shown in Fig. 10. The outside coating upon the belt is charged from a suitable source of static electricity J by means of the comb J', adjustably supported by a suitable connector J², mounted upon the pivoted portion 80 H at one end of the hopper, so that by swinging this end portion away from the belt the same may be examined or the take-ups S' at the ends of the belt adjusted to maintain the necessary tension. When it is desired to 85 work with the magnetic current alone, this end portion may be thrown back and the static charge disconnected from the belt. A similar end portion H' is provided at the opposite end of the belt. This belt is supported 90 throughout its length by a series of rollers P, of non-magnetic material, mounted upon a suitable support P', extending longitudinally between the upper and lower surfaces of the belt, and these rollers may, if desired, be provided with a coating of rubber, particularly 95 if formed of a metal. (See Fig. 10.)

The belt-frame P' and the belt carried there-

by are supported by springs X at the opposite ends thereof, which, as shown in Fig. 4, are provided with a horizontal portion X' at their upper ends and threaded at their lower ends X². These threaded portions pass through threaded sockets in sprocket-wheels X³, which are rotatably supported upon the frame of the machine and over which a sprocket-chain X⁴ passes for the purpose of operating the wheels on opposite sides of the shaft in unison in order to accurately level the belt and to adjust the same relative to the magnetic rollers.

The series of magnetic rollers M are suitably journaled in the framework of the machine, as will be hereinafter described, and adjacent to each a cleaner-roller N is rotatably mounted in coöperating relation thereto. Beneath each cleaner-roller a receiving-hopper O is provided and adapted to discharge by any desired means—for instance, a conveyor O', driven by belt O² from the cleaner, so that the material from the hopper B above the belt S is carried by said belt beneath the magnetic rollers, which remove the magnetic particles therefrom, and the tailings are finally discharged into the hopper A². These magnetic rollers are charged from any suitable source of current, such as the dynamo Z and line connection Z', extending to the terminal posts Z², which are provided with brushes Z³, and bearing upon a conducting-ring M', carried upon the shaft M³ of the magnetic roller M, the opposite ends of each shaft being thus connected to establish a circuit through the magnetic roller, and the series of rollers are suitably wired in circuit by means of the connectors Z⁴, as shown in Fig. 3.

The construction of the magnetic roller M and the cleaner-roller N is particularly shown in Figs. 6 and 7, wherein the pole-pieces I and I' are of opposite polarity and have a longitudinal extension I² secured to their peripheries. This extension is provided with a series of parallel grooves, thus providing a series of points upon each of the extensions extending peripherally thereof, which are of the same polarity as the pole-pieces. Between these extensions a gap or space I³ is provided, and the cross-section of the extensions I² is not sufficient to conduct all of the magnetic lines of force to this gap, so that these lines of force are practically distributed equally along the surface of the extension. The grooves or corrugations perform a very important function, as they individualize the magnetic lines of force at their outer points, and thus more readily sustain feebly-magnetic particles and also facilitate the removal of the magnetic particles by so concentrating them at these points that the cleaner-roller can readily receive and remove them in its rotative action. The grooves between the parts are filled with any desired non-magnetic material, so that the roller presents a smooth

periphery having a circumferentially-extending series of points of magnetic contact. The pole-pieces I and I' are spaced apart by suitable soft-iron sleeves M², disposed upon the shaft M³ of the magnetic roller to increase the cross-section of the magnet-core, which shaft carries the conducting-disk M', from which the wiring M⁴ receives its charge. This wiring is wound, preferably, as shown by the diagram in Fig. 8, so as to extend in reverse directions and positively charge each of the pole-pieces for the purpose of establishing a proper magnetic field.

The cleaner-roller N is provided with the shaft N', upon which an insulating-core N², of any desired material—for instance, wood—is secured, and upon the periphery of this core a series of magnetic sleeves or collars N³ are secured and may be formed of soft iron of the same dimensions longitudinally as the extensions of the pole-pieces for the magnetic roller. These sleeves or collars are provided with a series of grooves to form peripheral projections N⁴, which correspond to the points of the extensions I², so that in the rotation of the cleaner-roller these ribs travel directly over the points and remove therefrom the magnetic particles sustained thereby. The cleaner-roller N revolves in the same direction as the magnetic roller M, which causes the peripheries to pass in opposite directions at their point of nearest contact, and these peripheries may be either in contact or very near, so that the magnetic charge is collected upon the cleaner-roller at the point of nearest approach to the magnetic roller and of approximately the same strength as that of the magnetic roller. The magnetic particles of metal are unable to pass this point upon the magnetic roller and are attracted to and received by the cleaner-roller, by which they are carried over a hopper and discharged therein. The magnetic field weakens on the cleaner-roller in its rotation away from its point of nearest approach to the magnetic roller until a point is reached where the reduced magnetism is not sufficient to sustain the adhering particles.

Any desired driving means may be used for the purpose of actuating the several movable parts in the apparatus hereinbefore disclosed; but as illustrating a desirable form of such means we have shown in Fig. 1 a driving-shaft R, provided with a pulley R', from which a belt extends to any suitable source of power. This shaft R is also provided with eccentrics R², mounted thereon, from which a strap R³ extends to the frame of the belt S for the purpose of rapidly shaking the belt by a lateral movement thereof. The shaking device R² and R³ described forms one means for agitating the material; but any other desired means may be used for agitating the material in a direction other than the direction of feed through the magnetic field and in a plane sub-

stantially parallel with the pole or poles of the magnet. The shaft R is also provided at the hopper end with a driving-pulley R' for communicating power to the pulley R⁵ upon the shaft for the feed-shaker by means of the belt R⁶. This shaker C consists of an eccentric C', mounted upon the shaft of the pulley R⁵ and connected by a strap C² with the pan B' beneath the hopper. At the lower portion of the hopper a flexible flap B² is provided at the rear side thereof, and this pan is supported from the upper portion of the hopper by means of hangers B³, pivotally connected thereto at their lower ends. The adjustable strap B⁴ extends from the rear portion of the pan B' and is connected to the lower part of the hangers B³, so that the inclination of the pan relative to the lower portion of the hopper may be adjusted and maintained.

The driving-shaft R is also provided with a cone-pulley D, coöperating with a pulley D' and connected by a belt D², adapted to be adjusted by a threaded sleeve D³, operating upon a securing-shaft D⁴, which is provided at its outer end with a handle D⁵. These cone-pulleys are adapted to vary the speed of the several parts which are driven thereby.

The ore-belt S is driven from these cone-pulleys by means of a worm-gear. The shaft of the pulley D' is provided at one end with a worm D⁶, adapted to mesh with a gear-wheel F, carried upon a shaft F', which shaft at its opposite end is provided with the sprocket-wheel F², adapted to drive a sprocket F³ on the end of the shaft of the roll Q, which supports and drives belt S by means of a chain F⁴, extending from the sprocket F² to the sprocket F³. The idler-sprocket F⁵ may be disposed to bear upon the chain F⁴, as shown by dotted lines in Fig. 3, and adjusted to take up the slack in this chain when the ore-belt is raised or lowered for adjustment.

For the purpose of driving the magnetic rollers and cleaner-rollers the shaft F' is provided between its ends with a gear-wheel G, meshing with a gear G', the shaft of which is provided with a sprocket from which the driving-chain G² extends to a suitable sprocket G³, carried upon one end of the shaft of one of the magnetic rollers. The opposite end of the shaft of the magnetic roller is provided with a sprocket G⁴, from which a chain G⁵ extends to the sprocket G⁶ upon the end of the shaft of the cleaner-roller, by which means the latter is driven in the same direction as the magnetic roller. The several magnetic rollers are driven in unison by means of a sprocket-chain G⁷, extending the length of the apparatus and engaging sprockets upon each of the rollers, as shown by dotted lines in Fig. 3. This chain may be held under tension by means of the idler G⁸. (Shown in Fig. 3.) By means of these driving connections it will be seen that the speed of the shaft F' can be altered by means of the cone-pulleys and that

both the traveling ore-belt and the magnets are driven from this shaft, so as to reverse their direction of rotation and to preserve the same relative speed whenever the driving speed is altered. In practice the surface speed of the belt and the peripheral speed of the magnetic rollers are exactly the same, so that the momentum of the magnetic particles will not be retarded nor its speed increased by being taken up by the magnets.

In Fig. 5 this invention is shown in connection with a static separator of a type similar to that shown in Patents Nos. 670,440 and 670,441, in which the static charge for the ore-conveying belt S is received by induction from the main static separator-belt L, which is statically charged from a suitable brush or comb J⁶, communicating with a source of static electricity. The belt L of the main static separator passes beneath a suction device L', having a screened surface by which the metallic particles are repelled and through which the non-metallic particles are drawn by the suction. This screened surface is grounded by a conducting-wire J⁶, and the belt L passes over suitable driving-rolls L², from which it is insulated, while the frame L³ carries an induction static charge to the ore-conveying belt S beneath the magnets M, which magnets in turn receive an inductional charge from the belt and frame.

In the modified application of the invention shown in Fig. 9 the traveling ore-belt is omitted and the ore delivered from the hopper B⁶ directly onto the surface of the magnetic roller M⁶, from which the magnetic particles and flour-gold are removed by the cleaner-roller N⁶, which discharges into a hopper O⁶, communicating with a suitable receptacle O⁷, while the non-magnetic particles passing over the magnetic roller M⁶ are delivered into a suitable receptacle O⁸. In the apparatus shown in Figs. 1 to 4 the magnetic roller is charged with static electricity secured by induction from the belt S on the frame of the machine and magnetically energized from the dynamo Z or other suitable source, so as to exert its attractive influence upon the statically-charged belt from which the ore is fed. This belt is charged by induction from any suitable static generator, so that the particles of ore thereon are repelled from the belt toward the magnetic roller, which collects the magnetic particles and deposits them within the hopper through the action of the cleaner-roller. The material advantage of this arrangement is that the particles which are feebly magnetic are thus brought within the influence of the magnetic roller, which is thereby saved from exerting the lifting energy necessary to attract and move the magnetic particles within or under the mass of ore upon the belt. The charge of static electricity upon the belt causes the particles of ore to mutually repel each other while they are

being attracted by the statically-charged magnetic roller. In this manner the magnetic particles are rendered perfectly free to move in the lines of magnetic force and are not obstructed by the gangue of the ore.

With the use of the statically-charged magnetic roller it has been found that much of the very fine gold follows the magnetic particles, thus making a magnetic concentrate of the iron and gold. This is due to the well-known law that two particles statically charged at different potentials attract each other, and this attraction can be maintained as long as there is a difference of potential between the two bodies. When the ore comes into contact with the magnetically and statically charged roller, the non-magnetic particles are repelled therefrom, while the magnetic particles adhere thereto, together with some of the fine gold, the reason being that the iron particles having sharp corners do not retain their static charge the same as the gold, and consequently there is a constant difference of potential between the gold and iron particles, which causes them to adhere, the iron being carried by its magnetic attraction to the roller. While it is desirable in some instances to make a clean concentrate of the iron from the gold values, it frequently happens that when the gold is extremely fine it is advantageous to carry it with the iron, particularly when an electrically-repulsive screen is used to repel the metallic masses in the electrostatic separation. It has been found that a much greater difference of potential between the screens and statically-charged belt is required to separate very small metallic particles from the ore than for the separation of larger particles, and this difference of potential can only be maintained by increasing the distance between the belt and the screen, as thus a larger charge accumulates on each in an effort to bridge the intervening space. This action charges the metal within the field more strongly than otherwise; but at the same time it diminishes the amount of gangue that passes from the ore through the screen, as the discharge across this space is not as frequent as when the screens are close to the belt. The fine gold particles are but little more than points, and on account of the extremely small surface that they present a very strong static charge is required to control them, so that it will consequently be seen that if the fine particles of gold and the sharp angular iron are removed from the ore more of the static electricity can be used to move the gangue of the ore and less will be needed to control the larger metallic particles. The gold can be removed from the magnetic concentrates by a magnetic separator which is not statically charged.

In addition to the advantages and co-operation heretofore pointed out in relation to the magnetic and static separators it will be noted that by charging the surface of the

magnet with a static current while it is being energized by dynamic or voltaic electricity a joint concentration of the iron and fine gold is secured, thorough and economical. If a statically-charged belt be used beneath the magnetic roller, another very important advantage is secured in the separation.

It must be understood that we do not confine ourselves to statically charging the belt, for the same results are obtained by grounding the belt and charging the magnet-roller, and therefore either method may be used, depending on the nature of the material and the convenience of working the same. It will also be apparent that the magnetic separator may be used without the static charge when so desired and is adapted for use in other forms of separators than herein shown.

Many mineral substances have non-magnetic metallic bases, which become susceptible to magnetic attraction if they are simultaneously charged electrostatically, thus effecting a separation which cannot otherwise be secured. Assuming that the belt S is electrostatically charged with the positive sign, the magnetic roller M will be charged inductively with the negative sign, and there is a zero-line intermediate between these two surfaces where the opposing electrification of one surface will neutralize that of the other. Now if the ore be fed upon the belt in a thin layer the particles will be attracted toward the roller by the static force and on coming in contact therewith will be again repelled by the same force. In actual practice there are many of these substances which are partially conductive and do not actually come in contact with the magnet, but lose their initial electrification soon after crossing the zero-line into an opposing field. Consequently if the electrostatic charge is properly regulated these substances can be kept oscillating backward and forward across this zero, and thus practically suspended in space. Another feature of the electrostatic attraction is that the movement of particles of matter under this influence is very sluggish and this sluggishness is increased as the distance between the opposing surfaces is increased. Particles of matter under magnetic attraction move with celerity toward the inducing-magnet; but their speed is increased as the square of the distance is decreased, while with electrostatic attraction the velocity of the particles can be made practically uniform. This is due to the fact that the particles after passing the zero-line begin to lose their initial electrification, which loss varies with the dielectric medium used, which may be air, liquid, or any well-known medium. It will therefore be noted that the mass containing paramagnetic particles is electrically suspended in a dielectric medium, and the removal of these paramagnetic particles is effected by a magnetic force. Fur-

thermore, the ore upon the belt, the surface of which is statically charged, passes under the magnetic roller, which is similarly charged by induction and rises toward the magnet at the same time, spreading in all directions, which is caused by the mutual repulsion of the particles which have been statically charged. After touching the magnetic roller the non-magnetic gangue immediately returns to the belt, while the magnetic particles adhere and are removed by the cleaner-roller. The actual effect secured is that the ore mass loses its weight and the magnetic particles while being attracted by the magnet have no specific gravity or weight. The spreading effect is an important feature, as it opens the mass of ore and allows the magnetic particles to follow the true lines of magnetic force, as by the general mutual repulsion other particles come near to offer obstruction. It will also be obvious that the positive charging of the belt and the inductional charging of the magnetic roller may be reversed or otherwise arranged to secure a similar result.

It will be obvious that changes may be made in the details of construction and configuration of the several parts and of the auxiliary devices constituting parts of the apparatus without departing from the spirit of the invention as defined by the appended claims.

Having described the invention and set forth its merits, what we claim, and desire to secure by Letters Patent, is—

1. In an electrostatic magnetic separator, a magnetically-energized roller, and a statically-charged member adapted to convey ore to said roller and to charge the ore, substantially as specified.
2. In an electrostatic magnetic separator, a magnetically-energized roller, a statically-charged member adapted to convey ore to said roller, and means for discharging metal carried by said magnetic roller; substantially as specified.
3. In an electrostatic magnetic separator, a magnetically-energized roller, a statically-charged member adapted to convey ore to said roller, and means for magnetically discharging metal carried by said magnetic roller; substantially as specified.

4. In an electrostatic magnetic separator, a magnetically-energized roller, a statically-charged member adapted to convey ore to said roller, means for discharging metal carried by said roller, and a frame for said static member insulated therefrom and adapted to support and charge the magnetic roller; substantially as specified.

5. In an electrostatic magnetic separator, a magnetically-energized roller, a statically-charged member adapted to convey ore to said roller, means for discharging metal carried by said roller, a frame for said static member insulated therefrom and adapted to support and charge the magnetic roller, and a conveying

device above said static member for removing metallic particles; substantially as specified.

6. In a device of the class described, a magnetic roller comprising a series of plates, windings between said plates, lateral extensions carried by said plates and insulated from said windings, and a series of parallel conducting-ridges encircling the periphery of said extensions and insulated from each other by fillings within the intervening grooves; substantially as specified.

7. In a device of the class described, a constantly-energized magnetic roller having a series of magnetized faces, and a magnetic cleaner-roller inductively energized from the magnetic roller and adapted to lie adjacent to said faces and rotate in the same direction therewith; substantially as specified.

8. In a device of the class described, a magnetic roller comprising a series of magnetized faces insulated from each other, means for magnetizing said faces, means adapted to feed ore to said roller and an inductionally-charged cleaner-roller composed of a metallic face adapted to be inductively magnetized from the magnetic roller to collect material lifted thereby; substantially as specified.

9. In a device of the class described, a magnetic roller comprising a series of magnetized faces insulated from each other, means for magnetizing said faces, means adapted to feed ore to said roller, a cleaner-roller composed of an insulated body and metallic face adapted to be inductively energized by the magnetized roller, and a trough extending beneath said cleaner-roller; substantially as specified.

10. In a device of the class described, a magnetic roller comprising a series of magnetized faces insulated from each other, means for magnetizing said faces, means adapted to feed ore to said roller, a cleaner-roller composed of an insulated body and metallic face adapted to be inductively energized by the magnetized roller, a trough extending longitudinally beneath said cleaner-roller, and a conveyor within said trough for removing material from said trough; substantially as specified.

11. In a device of the class described, a feed-hopper, a shaker-pan disposed in a horizontal plane beneath the discharge therefrom, means for oscillating said pan transversely of the hopper-discharge, a flexible wall at the rear of said discharge, a hanger pivotedly supported from the upper portion of said hopper, means for pivoting said pan between its ends to said hanger at the lower end of said hopper, and an arm adjustably secured to the lower end of said hanger and pivoted to the rear of said pan; substantially as specified.

12. In a device of the class described, a magnetic roller comprising a shaft, a series of plates located therein, conducting-cores disposed between said plates, magnetizing-wind-

ings upon said cores, lateral faces at the peripheries of said plates, a conducting-ring communicating with one end of said winding, a cleaner-roller comprising an insulating-base, 5 and magnetic metal surfaces thereon disposed in alinement with the faces upon the magnetizing-roller; substantially as specified.

13. In a device of the class described, a magnet-roller comprising a shaft, a series of plates, 10 conducting-cores disposed between said plates, magnetizing-windings alternating in direction upon successive cores, lateral ribbed faces at the peripheries of said plates, a conducting-ring communicating with one end of said winding, a cleaner-roller comprising an insulating-base, 15 ribbed magnetic metal faces thereon disposed in alinement with ribs upon the magnetizing-roller, and means for rotating said cleaner-roller and the magnetic roller in the same direction; substantially as specified.

14. In an electrostatic magnetic separator a magnetized attractive surface, means for feeding material thereto and discharging therefrom a source of a voltaic current for energizing the same, and a source of static electricity to charge said surface, whereby metallic particles magnetically held by said surface will sustain other particles by reason of difference in potential thereof; substantially as 25 specified.

15. In a device of the class described, a statically-charged belt, a magnetic roller disposed above the same, and means for removing metal carried by said roller; substantially as specified.

16. In a device of the class described, a static separator, a statically-charged belt above said separator adapted to be energized by an inductional current therefrom, and a magnetic 40 roller charged by the inductional current from said static separator; substantially as specified.

17. A magnetic separator comprising a magnetically constantly-energized surface, means for feeding material thereto, and a cleaner rotatable adjacent to said surface and magnetically energized by induction therefrom to remove material from said separator; substantially as specified.

18. In a device of the class described, a traveling conveyer-belt and supporting-frame, means disposed above the same adapted to raise and convey material therefrom, a driving-shaft extending longitudinally of the belt, and carrying eccentrics, straps extending from said belt-frame to said eccentrics, a spring-support for said belt to permit vibration thereof, means for adjusting said belt vertically relative to the raising means above the same, a hopper extending longitudinally beneath 55 said belt, and rollers carried by the upper surface of said supporting-frame; substantially as specified.

19. In a device of the class described, a traveling conveyer-belt and supporting-frame, means disposed above the same adapted to raise

and convey material therefrom, a driving-shaft extending longitudinally of the belt and carrying eccentrics, straps extending from said belt-frame to said eccentrics, a spring-support for said belt to permit vibration thereof, means for adjusting said belt vertically relative to the raising means above the same, rollers carried by the upper surface of said support, supporting-rollers for said belt at opposite ends of said support, a speed-regulating device carried by said driving-shaft, and gear connections to said speed device to drive the belt-rollers; substantially as specified.

20. In a device of the class described, a traveling conveyer-belt, means disposed above the same adapted to raise and convey material therefrom, a driving-shaft extending longitudinally of the belt and carrying eccentrics, straps extending from said belt to said eccentrics, a spring-support for said belt to permit vibration thereof, means for adjusting said belt vertically relative to the devices above the same, a longitudinal support extending between the layers of the belt, rollers carried by the upper surface of said support, a speed-regulating device carried by said driving-shaft, geared connections to said speed device to drive the belt, and a driving connection therefrom for actuating the material-raising means above the belt relative to the speed of the belt; substantially as specified.

21. In an ore-separator, an ore-supporting surface comprising a body of insulating material, a metallic surface upon one face thereof, means for electrically charging said metallic surface, and a magnetic separator to collect from said surface; substantially as specified.

22. In a device of the class described, a conveying-belt, a magnetic separator to collect from said belt, a hopper for discharging material thereon, a receiving-hopper extending longitudinally beneath the belt, a pivotally-mounted end portion to said lower hopper disposed at one end of the belt, and a brush or comb carried by said end portion for electrically charging the belt; substantially as specified.

23. In a device of the class described, a conveying-belt, a magnetic separator to collect from said belt, a hopper for discharging material thereon, a receiving-hopper extending longitudinally beneath the belt, a pivotally-mounted end portion to said lower hopper disposed at one end of the belt, a brush or comb carried by said end portion for electrically charging the belt, a rotatable magnet above the belt, a support between the layers of the belt, and a bearing-roller upon said support beneath said magnet; substantially as specified.

24. In a device of the class described, a conveying-belt, a rotatable magnetic roller above the same, means for magnetically charging said roller, an inductively-magnetized cleaner-

roller adjacent to the magnetic roller, a hopper above said belt and beneath said cleaner-roller, and a conveyer in said hopper driven from said cleaner-roller; substantially as specified.

25. In a device of the class described, an ore-conveying belt supported for lateral vibration, a driving-shaft extending longitudinally of said belt and provided with eccentrics for vibrating the belt, a hopper having a shaking-pan beneath the same, a driving connection from said shaft to reciprocate said pan, a speed-regulating mechanism operatively connected to said shaft, a transverse counter-shaft driven from said speed-regulating mechanism, means carried by said counter-shaft for driving said belt, a rotatable magnet above said belt, and a gearing from said counter-shaft for rotating said magnet; substantially as specified.

26. In a device of the class described, an ore-conveying belt supported for lateral vibration, a driving-shaft extending longitudinally of said belt and provided with eccentrics for vibrating the belt, a hopper having a shaking-pan beneath the same, a driving connection from said shaft to reciprocate said pan, a speed-regulating mechanism operatively connected to said shaft, a transverse counter-shaft driven from said speed-regulating mechanism, means carried by said counter-shaft for driving said belt, a rotatable magnet above said belt, a gearing from said counter-shaft for rotating said magnet; a rotatable cleaner-roller adjacent to said magnet, and a gearing from said magnet to drive said cleaner-roller; substantially as specified.

27. In a device of the class described, an ore-conveying belt supported for lateral vibration, a driving-shaft extending longitudinally of said belt and provided with an eccentric for vibrating the belt, a hopper having a shaking-pan beneath the same, a driving connection from said shaft to reciprocate said pan, a speed-regulating mechanism operatively connected to said shaft, a transverse counter-shaft driven from said speed-regulating mechanism, means carried by said counter-shaft for driving said belt, a rotatable magnet above said belt, a gearing from said counter-shaft

for rotating said magnet, a rotatable cleaner-roller adjacent to said magnet, a gearing from said magnet to drive said cleaner-roller, a hopper beneath said cleaner-roller having a conveyer therein, and a gearing from said conveyer to said cleaner-roller; substantially as specified.

28. In a device of the class described, a conveying-belt, a magnetic roller above the same, spring-supports at the opposite sides of each end of said belt having threaded lower ends, means for laterally reciprocating said belt, fixed rotatable threaded sprockets to support and feed the spring-supports by engaging the threaded ends thereof, and chains for connecting the sprockets on opposite sides at each end of the belt to adjust those at either end simultaneously and each end independently; substantially as specified.

29. In a device of the class described, a conveying-belt, means for statically electrifying the same, a magnetic separator to collect from said belt, a supporting-roller at each end of the belt insulated from its journal, and a support for said rollers having an adjusting device for maintaining the belt under tension; substantially as specified.

30. In a device of the class described, a magnetic roller, a cleaner-roller adjacent thereto having an insulated body and a metallic sleeve or collar thereon provided with a series of peripheral projections; substantially as specified.

31. In a device of the class described, a cleaner-roller having an insulated body and a metallic sleeve or collar thereon provided with a series of peripheral projections, and a magnetic roller provided with a peripheral pole-piece having points or projections in alignment with those on the sleeve of the cleaner-roller; substantially as specified.

In testimony whereof we affix our signatures in presence of two witnesses.
